UNITED STATES PATENT OFFICE.

DOMENICO OTTAVIANI, OF DAYTON, OHIO.

SUBMARINE.

1,266,305.

Specification of Letters Patent. Patented May 14, 1918.

Application filed May 14, 1917. Serial No. 163,551.

To all whom it may concern:

Be it known that I, DOMENICO OTTAVIANI, citizen of the United States, residing at Dayton, in the county of Montgomery and State 5 of Ohio, have invented certain new and useful Improvements in Submarines, of which the following is a specification.

My invention relates to submarines or under sea boats and more particularly to submerging or diving apparatus for boats having a buoyancy characteristic or tendency to rise in the water thereby obviating the necessity for an excessive amount of water or other ballast.

10 The object of the invention is to simplify the construction as well as the means and mode of operation of such devices whereby they will not only be cheapened in construction but will be more efficient in use, positive 15

20 in operation, easily and quickly adjusted whereby the inclination of the boat to the horizontal may be easily and quickly varied and the depth at which the boat shall travel correspondingly varied.

25 A further object of the invention is to provide stabilizing means for the vessel whether traveling at or adjacent to the surface of the water or far below.

30 A further object of the invention is to enable the vessel to be submerged under the influence of the same propelling power which drives the vessel forward, whether at the surface or far beneath, and which will further enable the vessel to maintain a line of travel 35 below the water level which shall deviate but little from a straight line.

40 A further object of the invention is to provide improved means for indicating to the operator or crew the relative positions of the deflecting or submerging vanes.

With the above primary and other incidental objects in view as will more fully appear in the specification, the invention consists of the features of construction, the 45 parts and combinations thereof and the mode of operation or their equivalents as hereinafter described and set forth in the claims.

50 Referring to the drawings, Figure 1 is a side elevation of a submarine or under sea boat, broken away to disclose the driving mechanism, to which the invention forming the subject matter hereof has been applied. Fig. 2 is a bottom plan view thereof. Fig. 55 3 is a side elevation of a modification of the construction shown in Fig. 1 in which are

embodied multiple deflecting or submerging planes or vanes. Figs. 4 and 5 are detail sectional views on lines 4-4 and 5-5 of Fig. 1, respectively. Fig 6 is a detail view of the 60 indicator and the actuating means therefor. Fig. 7 is a detail perspective view of the end of the keel and the deflecting or submerging planes or vanes and their transverse connecting tie.

65 Like parts are indicated by similar characters of reference throughout the several views.

Referring to the drawings, 1 is the hull of the vessel of which 2 is the keel and 3 the 70 usual guiding rudder which controls the lateral deviation of the vessel. Mounted upon the hull 1 is the usual superstructure 4 and the periscope 5. Pivoted upon opposite sides of the keel 2 and capable of 75 oscillatory movement about pivotal connections 6 are two deflecting rudders or planes 7 which by their operation serve to deflect the vessel from an even keel position, guiding it either downward or upward according 80 to the direction of inclination of said deflecting rudders or planes. The deflecting rudders or planes 7 are located closely adjacent to the keel 2 in which positions they are overhung by the hull 1. Fins or guiding 85 rudders have heretofore been provided upon the sides of the hulls of submarine vessels in which instances they project laterally beyond the outline of the body or hull of the vessel. It is to be noted that in the present 90 construction the deflecting rudders or planes 7 underlie the hull of the vessel from which they are spaced, thereby forming an intermediate passage of sluice-way 8. The deflecting rudders or planes are carried upon 95 trunnions or arms 9 mounted on the keel 2. These arms or trunnions are supported at their outer ends by pendant links or supporting brackets 10.

100 Mounted in suitable bearings in the keel 2 at opposite sides of the pivotal connections of the deflecting rudders or planes 7 are vertically disposed rotary actuating screws 11 and 12. Located within a suitable housing or inclosure 13 adjacent to the hull or body 1 are bevel gear pinions 14 and 15 upon the screw shafts 11 and 12 respectively. Meshing with the gear pinions 14 and 15 are corresponding bevel gear pinions 16 and 17 located on the opposite ends of a longitudinally disposed connecting drive shaft 18. Either of the screw shafts 11 and 12 may be

extended upward as at 19 to afford a driving connection with an actuating motor or mechanism within the hull 1. In Fig. 1 the screw shaft 12 has been shown so extended 5 and provided at its upper end with a gear 20 meshing with a corresponding gear 21 upon a drive shaft 22 which carries a gear 23 meshing with a drive pinion 24 upon the armature shaft of a driving motor 25. Mounted 10 for vertical travel upon the shafts 11 and 12 as said screw shafts are rotated are cross arms 26 having therein screw threaded openings 27 engaging over said screw shafts 11 and 12. The cross arms 26 are preferably 15 cylindrical and mounted thereon are sleeves 28 engaging in keepers or housings 29 secured to the deflecting rudders or planes 7. These keepers or housings 29 are of sufficient size to permit a limited relative movement 20 of the sleeves 28 and arms 26 in relation with the deflecting rudders or planes 7 as the latter are oscillated to compensate for the varying inclinations of the rudders. In addition to being pivotally supported 25 upon the laterally disposed trunnion arms 9 and further supported and connected by the cross arms 26 carried by the screw shafts 11 and 12, the deflecting rudders or planes 7 are further connected adjacent to their extremities 30 by transverse tie bars 30 connected rigidly to the respective rudders or planes and extending through arcuate slots 31 in the keel 2. By this means the deflecting rudders or planes 7 are interconnected into 35 a rigid unitary structure disposed on opposite sides of the keel 2. It is to be noted that the driving connections between the screw shafts 11 and 12 comprising the gear pinions 16 and 17 and the intermediate drive 40 shaft 18 are such that the screw shafts 11 and 12 will be operated in opposite directions. That is to say that when the screw shaft 11 is operated to drive the cross arms 26 carried thereby downward, screw shaft 12 45 is rotated in the opposite direction to actuate the cross arms 26 carried by said shaft 12 upwardly in unison with the descent of the cross arms 26 of the opposite screw shaft. Thus the opposite ends of the deflecting rudders or planes 7 are positively moved in 50 unison in opposite directions thereby effecting an oscillatory movement of the rudders or planes 7 about their central pivotal connection 9. In order to indicate to the operator or crew the relative adjustment of the planes or rudders 7 there is provided upon the extension 19 of the shaft 12 a sprocket wheel 32 connected by a sprocket chain 33 with a similar sprocket 34 upon a vertically 55 disposed shaft 35. The shaft 35 carries at its upper end a worm gear 36 meshing with a worm wheel 37 to the shaft of which is attached an indicator hand or pointer 38 which travels to and fro over an indicator dial 39 to indicate the different positions of 60

adjustment of the deflecting planes or rudders 7. The construction is such that by depressing the rudders or planes 7 downwardly and forwardly the driving propeller 40 of the vessel will propel the hull 1 forwardly 70 and downwardly in an inclined course determined by the relative adjustment or inclination of the deflecting rudders or planes 7. When the vessel has descended to the desired level the deflecting rudders or planes are returned toward but not entirely to their neutral or horizontal position. It will be found necessary to make a slight inclination of the rudders or planes 7 sufficient to overcome the natural buoyancy of the vessel to maintain 80 the vessel at the desired depth. As the vessel is driven forward the movement of the water through the contracted passage or sluice-way 8 intermediate the deflecting rudders or planes 7 and the under side of the 85 hull 1 has a materially advantageous effect in forcing the vessel downward at an inclination to the horizontal, as well as a stabilizing effect in preventing rolling or sudden variations or changes of position. These 90 deflecting planes or rudders 7 arranged in spaced relation below the hull 1 also afford a stabilizing effect thought to be due to the passage of water through the passageway or sluice-way 8 intermediate the planes of rudders 95 7 and the under side of the hull which is not attained by the use of fins or rudders projecting from the hull itself. This stabilizing influence of the deflecting planes or rudders is felt when the vessel is riding on 100 even keel with the rudders substantially horizontal with the under side of the hull, as well as when being driven at an inclination to the horizontal, either during submerging or emerging operation. During the 105 submerging operation, the planes or rudders 7 are directed downwardly and forwardly and the vessel is driven forward by the propeller 40, planes or rudders 7 serve to simultaneously deflect it downward to greater 110 depth in unison with its forward movement. However, upon the emerging operation the planes are returned toward normal or parallel position only sufficient that the buoyancy 115 of the vessel may overcome the influence of the inclination of the rudders or planes 7 whereby the vessel will tend to rise. However, if it is desired to emerge quickly the relative positions of the deflecting rudders or planes 7 may be reversed and by directing the rudders upwardly and forwardly, the vessel may be quickly brought to the surface. 120

In the modified construction shown in Fig. 7, double sets of deflecting rudders or planes are employed. In lieu of the single set of rudders 7 it may be desirable in vessels of greater length or when greater degrees of inclination of the rudders are to be desired, to provide the vessel with mul- 125 130

multiple sets of such deflecting rudders or planes as shown at 41 and 42, Fig. 7. These planes 41 and 42 are pivoted at their central points 43 in the manner before described. Each set of deflecting rudders or planes is provided with actuating screw shafts 44-45 and 46-47, respectively. Each of these shafts is provided adjacent to its upper end and within the pendant housing 13 beneath the hull 1 with a bevel gear 48 each of which meshes with a corresponding gear 49 upon the intermediate longitudinally disposed drive shafts 50, 51 and 52. It is to be noted that the gear train is so arranged that the direction of rotation of the several screw shafts is alternated. These screw shafts are provided with the cross arms before described which are engaged with the deflecting rudders or planes 41 and 42, thereby serving to positively oscillate the deflecting rudders 41 and 42 in unison. The said rudders or deflecting planes are always adjusted simultaneously to the same degree of inclination and serve the same purposes and produce the same beneficial effects as those before described. It will be obvious that with a set of deflecting rudders or planes of great length the range of possible variation or inclination would be very limited whereas by employing multiple sets of such deflecting rudders or planes such rudders or planes may be adjusted to much greater degrees of inclination. Likewise the supporting connections of the rudders or planes are brought more closely together thereby affording a more rigid construction.

From the above description it will be apparent that there is thus produced a device of the character described possessing the particular features of advantage before enumerated as desirable but which obviously is susceptible of modification in its form, proportion, detail construction and arrangement of parts without departing from the principle involved or sacrificing any of its advantages.

While the invention has been described in language more or less specific as to certain structural features, it is to be understood that it is not limited to any specific details but that the construction and mode of op-

eration herein described comprise but one method of putting the invention into effect and the invention is therefore claimed broadly in any of its possible forms or modifications within the scope of the appended claims.

Having thus described my invention, I claim:

1. The combination with a vessel having a pendant keel, of oscillatory deflecting planes pivoted to the keel beneath the hull of the vessel, vertically disposed screw shafts mounted in the keel, cross arms screw threaded upon the shafts and engaged with the opposite ends of the oscillatory planes, and means for simultaneously driving said screw shafts to actuate said cross arms in opposite directions whereby said planes will be adjusted to different degrees of inclination.

2. The combination with a vessel having a pendant keel, of oscillatory deflector planes located upon opposite sides of the keel beneath the hull of the vessel and overhung thereby, rotary screw shafts mounted in the keel, means for simultaneously rotating the shafts, and cross arms actuated by the shafts and connected to said planes whereby the inclination of the planes is varied by the operation of said screw shafts.

3. The combination with a vessel having a pendant keel, of an oscillatory deflecting plane supported adjacent to its opposite ends at separated points upon the keel beneath the hull of the vessel, and means for varying the inclination of the plane in relation with the hull.

4. The combination of a vessel having a pendant keel, parallel deflecting planes mounted for oscillatory movement upon opposite sides of said pendant keel and transverse tie members extending through openings in said pendant keel connecting said parallel planes one to the other for movement in unison.

In testimony whereof, I have hereunto set my hand this 28 day of April, A. D. 1917.

DOMENICO OTTAVIANI.
